[57] CLAIM

The ornamental design for an armrest, as shown and described.

DESCRIPTION

FIG. 1 is a perspective view of an armrest embodying my design;

FIG. 2 is a right side elevational view of the armrest shown in FIG. 1;

FIG. 3 is a top plan view of the armrest shown in FIG. 1;

FIG. 4 is a bottom plan view of the armrest shown in FIG. 1;

FIG. 5 is a front elevational view of the armrest shown in FIG. 1; and,

FIG. 6 is a rear elevational view of the armrest shown in FIG. 1.

The broken line matter shown in FIG. 1 is shown for environmental purposes only.
